JOHN RUSSELL, OF PRAIRIE, MISSOURI.

Letters Patent No. 99,353, dated February 1, 1870.

IMPROVEMENT IN STEP-SUPPORTS FOR MILL-SPINDLES.

The Schedule referred to in these Letters Patent and making part of the same.

To all whom it may concern:

Be it known that I, JOHN RUSSELL, of Prairie, in the county of Clinton, and State of Missouri, have invented a new and useful Improvement in Step-Supports for Mill-Spindles; and I do hereby declare that the following is a full, clear, and exact description thereof, which will enable others skilled in the art to make and use the same, reference being had to the accompanying drawings, forming part of this specification.

This invention relates to improvements in the adjusting devices for the steps of mill-spindles; and consists in the arrangement of the steps in the top of a vertically-adjustable tube or other sliding support, provided with vertical guides, and working through guide-plates, to insure the vertical position and to prevent rattling, the said supports being mounted on a rod rising up from the bridge-tree and jointed to it, so that the joint may compensate for the curve described by it, due to the one end of the bridge-tree being fixed, and the other swinging around the said fixed point, and the steps may be raised in a right line.

Figure 1 represents a side elevation of my improved arrangement, and

Figure 2 represents a sectional elevation of the same, taken on the line xx of fig. 1.

Similar letters of reference indicate corresponding parts.

A represents a part of the "husk"-frame, and B, the bridge-tree. The steps for the spindles are commonly set on these bridge-trees, and, owing to the curves described by the said steps in raising and turning the free ends by the adjusting-screws C, for raising or lowering the stone, for grinding coarser or finer, it is impossible to keep the said spindles perpendicular to the faces of the bed-stones.

To avoid this difficulty, I propose to place the bridge-

trees lower down, and introduce the step-supports D, which may consist of hollow tubes, on the tops of which, the steps E, of any approved construction, may be fixed in any suitable way, supporting the said step-supports on rods F, jointed to the bridge-tree, and placing them in holes in guide-plates G, fixed to the beams H.

I also attach the broad lateral arms I to the support D, and provide the vertical adjustable guide-plates K to press against the said arms, and to be adjusted exactly perpendicular to the face of the bed-stone by the adjusting-screws L, so as to guide the support properly in working up and down, and to prevent it from chattering or rattling against the edges of the plates G, through which it passes.

The plate I, which forms the lateral arms, in this example, passes through the tubular support, and rests inside thereof, in the notched upper end of the rod F.

It will be seen, that by this arrangement, no matter how much the bridge-tree is raised, the foot of the spindle, resting in the step E, will always rise in a vertical line, or in a line perpendicular to the face of the bed-stone, as it may be without any deviation.

Having thus described my invention, I claim as new, and desire to secure by Letters Patent—

The combination of the hollow tubular support D, jointed rods F, lateral arms I, guide-plates G K, and adjusting-screws L, with the step E, all arranged as set forth, and operating to retain the spindles always in a true perpendicular position with respect to the bed-stone.

JOHN RUSSELL.
